UNITED STATES PATENT OFFICE.

CHARLES C. CALVERT, OF LODI, CALIFORNIA.

AUTOMATIC-FEED NAIL STRIPPER.

Application filed November 20, 1922. Serial No. 601,996.

To all whom it may concern:

Be it known that I, CHARLES C. CALVERT, a citizen of the United States, residing at Lodi, county of San Joaquin, State of California, have invented certain new and useful Improvements in Automatic-Feed Nail Strippers; and I do declare the following to be a full, clear, and exact description of the same, reference being had to the accompanying drawings, and to the characters of reference marked thereon, which form a part of this application.

This invention relates to improvements in nail stripping machines such as are commonly used in connection with box making and the like.

The principal object of my invention is to provide a device of this character with a means for automatically feeding the nails into the stripper-channels as the box shook to be nailed is slid into the usual holding form.

This feature eliminates the necessity of the box maker having to continually stop in his work to feed nails into the stripper chutes, as must be done with the machines in use at present, and which cuts down his output of boxes to a marked degree.

A further object is to arrange the feed actuating means so that the stripper and nail holding box do not have to bear a fixed and unchangeable relation to the box form, but they may be adjusted as to the space therebetween, or their height relative to each other, may be altered to suit the individual worker.

A further object of the invention is to produce a simple and inexpensive device and yet one which will be exceedingly effective for the purposes for which it is designed.

These objects I accomplish by means of such structure and relative arrangement of parts as will fully appear by a perusal of the following specification and claims.

In the drawings similar characters of reference indicate corresponding parts in the several views.

Fig. 1 is a perspective view of the complete apparatus showing the same as arranged in connection with a box-form.

Fig. 2 is a fragmentary longitudinal section of the nail container, and the nail feeding mechanism.

Fig. 3 is an end view of the feed-actuating device, showing the same as positioned in connection with a box form.

Referring now more particularly to the characters of reference on the drawings, the numeral 1 denotes a box having a lid 2 which is adapted to be held in a vertical position when desired by strap braces 3. Mounted in the lid a predetermined distance above the box and extending thereover is a tray 4, the outer end of which is open at and across the bottom to form a discharge 5, said bottom adjacent said discharge being formed as an apron 6 sloping downwardly thereto.

Under said discharge is a chute 7, sloping downwardly toward the lid 2, the chute being longitudinally grooved as at 8, said grooves communicating with slotted nail-holding members 9 extending beyond the chute, for the purpose as usual of holding nails in single file alinement. The chute is pivoted or hinged transversely to the tray 4, the lower end of the members 9 being connected by a cross-bar 10 which is removably held or connected to the braces 3 at any one of a number of vertically spaced points thereon, so that the angle of the chute structure may be altered at will.

The parts thus far described are common to the usual form of nail-stripper, and the members 4 and 7 are adapted to be moved to lie in the box, and the lid of the latter to be then lowered to enclose the same.

My improved automatic feeding mechanism comprises a screw-shaft 11 extending longitudinally and centrally of the tray 4 journaled in boxes 12 mounted at the upper and opposite ends of the tray.

Mounted on the outer end of the shaft is a spider comprising a plurality of substantially radial fingers 13 which are adapted to project, to a certain extent, into the discharge opening 5 adjacent the end of the apron 6. Slidable in the tray and extending transversely thereof is a pusher plate 14 to which is fixed an inverted V-shaped yoke 15 having vertical slots 16 which straddle the shaft 11, the upper edge of the forward slot and the lower edge of the rear slot being adapted to engage with the shaft.

By means of this construction, if a lot of nails are placed in the tray ahead of the plate 14 and the latter moved by hand into engagement therewith, when the shaft is rotated the said plate will then be moved forward, forcing the nails toward the spider and into the discharge. The function of the

spider is to engage the nails as they project into the path of movement thereof and prevent the nails from packing, as is their tendency to do. The nail-pack will then be 5 broken and the nails will then fall freely down and into the chute, a certain percentage dropping into the members 9, as usual, the nails not caught by said members being placed back into the tray again by the 10 operator at his convenience.

When the plate 14 has moved forward to its limit of travel in that direction, it may be returned to the opposite end of the tray by hand by merely tilting it so that the 15 shaft 11 is free of the slot edges, allowing of said plate being slid along on the shaft without disturbing the latter.

The shaft 11 is rotated by means of a flexible enclosed shaft structure 17 of any 20 standard design which is connected at one end to the inner end of the shaft 11 and extends thence to a supporting bracket or pedestal 18 adapted to be mounted on the working bench 19 on which the box 1 is 25 mounted, and positioned between said box and the box-making form 20.

Driven from said shaft 17 by bevel gears 21 or otherwise is a vertical extension 22, on which is mounted a ratchet or friction 30 wheel 23, a one-way spring-clutch mechanism 24 being interposed between said wheel and shaft extension, so that rotation of said extension, which may be considered as a part of the shaft 17, will only be had with a 35 movement of said wheel in one direction.

Auxiliary means may also be provided if desired for rotating said shaft 17, will only be had with a movement of said wheel in one direction.

40 Auxiliary means may also be provided if desired for rotating said shaft in the same direction independent of the wheel 23, this means comprising a sprocket wheel 25 on the shaft 17, driven by a chain 26 leading to any suitable actuating means such as a foot treadle (not shown) there being also a one-way spring clutch structure 27 interposed between said sprocket wheel and shaft.

45 In this manner, the shaft may be rotated intermediate the rotative periods of the wheel 23, which are intermittent.

The wheel 23 is positioned so as to slightly overhang the inner face of the form 20, so as to be frictionally engaged and rotated by 55 a box-shook 28 as the latter is slid into place in the form against said inner face thereof. The clutch structure 24 allows the wheel to again rotate as the shook is withdrawn without imparting rotation to the shaft, while 60 the clutch 27 allows of rotation of said shaft when actuated by the wheel 23 without imparting rotation to the wheel 25.

65 It will therefore be seen that every time a shook is inserted in the form, some of the nails in the tray will be automatically fed

into the holding members 9, without any attention on the part of the box maker being necessary, and a supply of nails sufficient for the needs of the worker is maintained in said members at all times.

70 From the foregoing description it will be readily seen that I have produced such a device as substantially fulfills the objects of the invention as set forth herein.

75 While this specification sets forth in detail the present and preferred construction of the device, still in practice such deviations from such detail may be resorted to as do not form a departure from the spirit of the invention, as defined by the appended 80 claims.

Having thus described my invention, what I claim as new and useful and desire to secure by Letters Patent is:

1. A nail stripping device including a nail 85 tray, a discharge chute leading therefrom, means mounted in the tray for forcing any nails therein toward the chute and moving means projecting into the mass of nails for agitating and preventing the packing of the 90 same prior to their entry into the chute.

2. A nail stripping device including a nail tray, a discharge chute leading therefrom, a transverse plate in the tray adapted to be positioned behind any nails therein, means 95 for moving said plate in a direction to force the nails toward the chute, and means actuated by said first named means for preventing the packing of any nails prior to their entry into the chute.

100 3. A nail stripping device including a nail tray, a discharge chute leading therefrom, a transverse plate in the tray adapted to be positioned behind any nails therein, a rotatable screw-shaft engaging said plate and arranged to move the latter forward as the shaft rotates, and a plurality of fingers mounted on the shaft adjacent the entry of the chute from the tray and projecting into the path of movement of said nails.

105 4. A nail stripping device for box-makers using a form in which to slide the box shook, including a nail tray, a discharge chute leading therefrom, means mounted in the tray for forcing any nails therein toward the chute, and means actuated by the movement of a shook into the form for actuating said first named means.

110 5. A nail stripping device for box-makers using a form in which to slide the box shook, including a nail tray, a discharge chute leading therefrom, a member mounted in the tray for forcing any nails therein toward the chute, a rotatable shaft for actuating said member, and means actuated by the movement of a shook into the form for rotating said shaft.

115 6. A nail stripping device for box-makers using a form in which to slide the box shook, including a nail tray, a discharge chute lead- 120

ing therefrom, and means actuated by the movement of a shook into the form for causing nails to be automatically fed from the tray into the chute.

5 7. A nail stripping device for box-makers using a form in which to slide the box shook, including a nail tray, a discharge chute leading therefrom, a member mounted in the tray for forcing any nails therein 50 toward the chute, a friction wheel positioned to be engaged by a shook as it is moved into the form, and means between said wheel and said member for moving the latter with the rotation of said wheel.

10 8. A nail stripping device for box-makers using a form in which to slide the box shook, including a nail tray, a discharge chute leading therefrom, a member mounted in the tray for forcing any nails therein toward 55 the chute, a rotatable shaft mounted on the tray and operatively connected to said member to move the same, a friction wheel positioned to be engaged by a shook as it is moved into the form, and driving shaft 60 means between said wheel and the first named shaft.

15 9. A nail stripping device for box-makers using a form in which to slide the box shook, including a nail tray, a discharge chute leading therefrom, a member mounted in the tray for forcing any nails therein toward 65 the chute, a rotatable shaft mounted on the tray and operatively connected to said member to move the same, a friction wheel positioned to be engaged by a shook as it is moved into the form, and a flexible shaft structure 70 connected at one end to the wheel and at the other end to the first named shaft, whereby the position of the wheel relative to the tray

20 40 10. A nail stripping device for box-makers using a form in which to slide the box shook, including a nail tray, a discharge chute leading therefrom, a member mounted in the tray for forcing any nails therein toward 75

45

the chute, a rotatable shaft mounted on the tray and operatively connected to said member to move the same, a friction wheel positioned to be engaged by a shook as it is moved into the form, driving shaft means 50 between said wheel and the first named shaft, and means between said wheel and the driving shaft means whereby the latter will only be rotated with a movement of the wheel in one direction. 55

11. A nail stripping device for box-makers using a form in which to slide the box shook, including a nail tray, a discharge chute leading therefrom, a member mounted in the tray for forcing any nails therein toward 60 the chute, a rotatable shaft mounted on the tray and operatively connected to said member to move the same, a friction wheel positioned to be engaged by a shook as it is moved into the form, driving shaft means 65 between said wheel and the first named shaft, and a one-way spring clutch mechanism interposed between the wheel and drive shaft, the wheel being turnably mounted on the latter. 70

12. A nail stripping device for box-makers using a form in which to slide the box shook including a nail tray, a discharge chute leading therefrom, a member mounted in the tray for forcing any nails therein toward 75 the chute, a rotatable shaft for actuating said member, means actuated by the movement of a shook into the form for rotating the shaft, and independent means for likewise rotating the shaft. 80

13. A nail stripping device for box-makers using a form in which to slide the box shook including a nail tray, a discharge chute leading therefrom, means actuated by the movement of a shook into the form for causing 85 nails to be automatically fed from the tray into the chute, and independent means for likewise causing the nails to be so fed.

In testimony whereof I affix my signature.

CHARLES C. CALVERT.
